SEALED IGNITRON

August P. Colaiaco, Pittsburgh, Pa., assignor to
Westinghouse Electric Corporation, East Pittsburgh, Pa., a corporation of Pennsylvania

Application March 8, 1947, Serial No. 733,395

3 Claims. (Cl. 250—27.5)

1

My invention relates to a vapor-electric device and particularly to means for maintaining sealed off vapor-electric devices in operating condition for an extended period of time.

In the operation of vapor-electric devices, it is frequently desirable to seal off the devices and operate them without the benefit of pumping equipment. Heretofore, this has resulted in a shortened period of operating life because during operation certain quantities of gas will leak through the container walls of even the best constructed containers. Also, in spite of heavy treating out, certain quantities of gas will be liberated during operation of the devices, particularly during faulty operation, such as arc back, when not only severe thermal but electrical conditions operate to release occluded gases.

The contamination of the devices by liberation or leakage becomes progressively worse so that after a more or less lengthy life period, the operation of the device becomes erratic and eventually completely unsatisfactory.

According to my invention, I provide means for trapping and storing the occluded gases which are liberated or which leak into or otherwise contaminate the interior of the device so that the useful life of a device is greatly extended. For this purpose, I provide a small sealed compartment within the container of the device and a relatively small pumping device for forcing the contaminating gases into the compartment where they are maintained by suitable trap valves. Preferably, the pump is provided in the form of a miniature vapor jet pump operated by vaporized cathode material, usually mercury, the vaporizing element being controlled from the exterior of the device and may conveniently be applied to a portion of the exterior to supply heat to a quantity of cathode material within a pump boiler wholly or partially within the vapor-electric device.

It is an object of my invention to provide pumping means for segregating contaminating gases in a sealed off container.

It is a further object of my invention to provide a vapor-electric pump operable at will to remove contaminating gases into a restricted portion of a container.

Other objects and advantages of my invention will be apparent from the following detailed description, taken in conjunction with the accompanying drawing, in which the figure is a fragmentary elevation partially in section of a vapor-electric device embodying my invention.

In the exemplary embodiment of my invention, 55

a vapor-electric device in the form of a vapor arc converter valve, has an exterior container 1 or chamber in which is contained a pool-type cathode 2 resting on the bottom 3 of the container 1 and cooperating therewith is an anode 4 supported in insulated relation to the rest of the device by a suitable insulating means 5. Control or deionizing means 6, such as anode and cathode shields with or without external connections, may be provided. Suitable exciting means, such as a make-alive electrode 7, is provided for initiating the conducting intervals.

In order to provide a sealed chamber in which to trap contaminated gases, I have provided adjacent the wall of the container 1 and preferably configured to conform thereto a substantially closed box-like chamber 10, preferably substantially rectangular in cross section. Adjacent this chamber 10 and preferably contiguous to the cathode surface, I provide a pump barrel 11, preferably in the form of a substantially straight tubular member having one side thereof in intimate thermal contact with a cooled external surface of the container 1, preferably that portion of the container which is cooled by an external cooling means, such as a water jacket 8, and normally used for condensing the vapors generated during operation of the device. Adjacent this pump barrel 11 is a boiler 12 for generating pumping fluid. This boiler 12 is provided with suitable heat generating means, such as an electrical heat generating unit 14 secured to the exterior thereof and supplied with electric current from a source not shown. Within the pump barrel is a vapor chimney 15 fed from the boiler 12 and having a diffusing nozzle 16 for entrapping and carrying away any vapors or gases within the container 1.

While any number of stages may be used, I prefer to use a plurality of pumping stages, the first one of which is a diffusion nozzle 16 and the other of which may be an entraining jet 17. An exhaust port 18 is provided in the pump barrel 11 and a tubular connection 19 extends from the exhaust port 18 into the restricted container 10.

In order to prevent reverse flow of gases from the restricted chamber 10 back through the pumping means, a one-way valve or trap is provided in the form of a depressed portion 20 within the chamber 10 into which will be carried or may be initially placed a quantity of cathode material having a relatively large surface area with respect to the cross sectional area of the tubular connection 19 between the pump and the container 10. At least the terminal portion of

the tubular connection 19 will dip below the surface of the cathode material contained within the depression 20 and will extend upwardly for such a height as may be necessary to prevent, by the weight of the trapped materials, the return flow of gases through the connection 19. The surface area of the depression 20 is relatively large in proportion to the cross sectional area of the tubular connection 19 so that a relatively small displacement of the surface on this area will produce sufficient material to provide a sealing height in a tubular passage 19. Preferably also an overflow 21 is provided so that any excess cathode material may return to the cathode proper. This overflow connection 21 is preferably made in the form of a tubular passage, the top of which extends to the desired maximum level of the material within the trap and extends sufficiently deep into the cathode material 2 that the pressure of the trapped gases will not displace the cathode material to thereby escape into the container. Also, this overflow tube 21 is preferably of sufficiently large cross section that drops of cathode material, such as mercury, on returning to the cathode will not entrap portions of the sequestered gas and thereby unwillingly contaminate the container.

The pump barrel 11 being in contact with a portion of the container wall serves as a condensing medium for the pump material, but because of the relatively inefficient cooling a quantity of cathode material will normally flow through the connection 19 into the trapped container 10 where it will condense and return through the overflow 21 to the cathode 2.

During non-operating conditions of the pump, the level of the cathode material in the boiler 12 and in the cathode dish 3 will assume substantially identical levels. However, when heat is applied to the boiler 12, vapor will be generated which creates a pressure within the boiler and displaces the cathode material and care must be taken that the boiler 12 is sufficiently deep that the operating pressure does not expel all of the cathode material and thus render the boiler inoperative. Preferably, the boiler 12 is completely sealed with respect to the pump barrel 11 so that all vapors must pass through the pump chimney 15 and a return connection 22 is provided from

the pump barrel 11 to a point adjacent the bottom of the boiler 12 so that condensed pumping material may return to the boiler 12. Also, it is desirable to provide a tubular connection 23 from a point below the normal cathode surface to a point adjacent the bottom of the boiler 12 so that cathode material may freely flow either in or out of the boiler 12 as the variations in pressure may require.

10 It will be noted that the cross sectional area and the capacity of the pump boiler 12 is relatively small with respect to the total cross sectional area and capacity of the cathode dish 3 so that the displacement of cathode material from the pump boiler 12 during operation of the pump does not materially affect the cathode level or produce undesirable flooding of any portion of the device.

20 While for purposes of illustration I have shown and described a specific embodiment of my invention, it will be apparent that changes and modifications can be made therein without departing from the true spirit of my invention or the scope of the appended claims.

25 I claim as my invention:

1. In a vapor-electric device having a substantially sealed container, a diffusion pump in said container, means exterior of said container for activating said pump, a normally sealed compartment in said container, an exhaust connection from said pump to said compartment and a reverse flow seal in said connection.

2. In a sealed off vapor-electric device, means for maintaining the working pressure comprising a vapor pump in said container, a pump boiler, means exterior to said container for applying heat to said boiler, a sealed compartment, an exhaust passage from said pump to said compartment, and a liquid seal for said passage.

3. In a sealed vapor-electric device having a cooled condensing surface, a pump barrel in good thermal conducting relation to said cooled condensing surface, a vapor jet in said barrel, means external to said container for controlling vapor flow to said jet, a closed compartment in said device, a vapor passage between the pump barrel and the compartment and a unidirectional valve means in said passage.

AUGUST P. COLAIACO.
